UNITED STATES PATENT OFFICE.

EMMANUEL LOUIS PAUL COLARDEAU, OF PARIS, FRANCE, ASSIGNOR TO HENRY CROCHAT, OF PARIS, FRANCE.

EXPLOSION-ENGINE.

1,307,896.

Specification of Letters Patent. Patented June 24, 1919.

Application filed October 22, 1918. Serial No. 259,219.

To all whom it may concern:

Be it known that I, EMMANUEL LOUIS PAUL COLARDEAU, engineer, citizen of the French Republic, residing at Paris, France, 5 have invented certain new and useful Improvements in Explosion-Engines, of which the following is a specification.

The invention relates to installations comprising either several internal combustion 10 engines or a single engine divided into elements independently fed.

It has for its chief object to enable such installations to be built so that the mechanical powers of the engines or engine elements 15 which they comprise, should be balanced for any power, and more particularly for slow working of the said engines, and this without the necessity of using a single carbureter for the feeding of the said engines or engine 20 elements.

The invention also consists in providing an independent carbureter for each engine or engine element, and in providing each carbureter with a throttle which is not controlled automatically by the corresponding engine or engine element, and in so connecting together on the engine side of the throttle the suction pipes of the carbureters, as to 25 produce an equilibrium between the pressures obtaining in the said parts of the suction pipes of the various carbureters.

The single figure of the accompanying drawing shows diagrammatically an installation of two engines according to the invention.

An ordinary independent carbureter a , a^1 is used comprising a throttle b , b^1 controlled by hand, and the suction pipe of the said carbureter is connected to the admission c , c^1 40 of the corresponding engine. Preferably, in the suction pipe of each carbureter between its throttle b , b^1 and the engine, is arranged a butterfly valve d , d^1 automatically controlled by the engine and adapted to control automatically the speed of the said engine. According to this invention, that part 45 of the suction pipe of one of the carbureters a , which is between the throttle b and the butterfly valve d is connected by a conduit e

to the corresponding part of the suction pipe of the other carbureter a^1 . Thus an installation is obtained, in which the two engines are supplied in an identical manner, even if the throttles of the two carbureters are not opened to exactly the same extent, since the conduit e equalizes the pressures in that part of the suction pipe of the two carbureters, which is on the engine side of the throttle. This arrangement is chiefly of importance for the low speeds of the engines, that is to say for small outputs of the carbureters; since, when the throttle of a carbureter is opened, the power of the engine supplied by the said carbureter, increases, first rapidly when the throttle is slightly open, and then more and more slowly as the throttle is opened more and more fully. For that reason, the conduit e being of no importance except for small outputs, can be made of a comparatively small cross-section.

This very simple arrangement makes it possible to obtain the same results as if the various engines were supplied by a single carbureter, and at the same time complications of piping are avoided. It is more suitable than a single carbureter, in the cases where it may be desired to work only one of the engines of the installation, since it is necessary only to provide a cock or valve in the conduit e .

Obviously the invention can be applied to a poly-cylindrical engine comprising several groups of cylinders, where each group of cylinders must be supplied by an independent carbureter.

Having now particularly described and ascertained the nature of my said invention and in what manner the same is to be performed, I declare that what I claim is:

1. An installation comprising either several internal combustion engines or a single engine divided into independently fuel-fed elements, in which each engine or engine element is supplied by an independent carbureter provided with a throttle which is not controlled automatically by the corresponding engine or engine element, characterized by the suction pipes of the various carbureters.

reters being connected together on the engine side of the throttle.

2. An installation as set forth in claim 1, characterized by the suction pipes of the various carbureters being connected together by a conduit of a relatively very small cross-section.

In testimony whereof I have hereunto set my hand in presence of two subscribing witnesses.

EMMANUEL LOUIS PAUL COLARDEAU.
